ROTARY IMPACT TYPE SCREW DRIVER

George W. Allen, Erving, Mass.

Application March 13, 1947, Serial No. 734,503

1 Claim. (Cl. 145—50)

1

The present invention relates to new and useful improvements in screw drivers and equivalent bit-type tools and has more particular reference to means attached to the handle equipped end of a screw driver shank for building up and transmitting extra force such as is often necessary in both seating and unseating screws.

The principal object of the invention is to provide hand-held hammer-driven mechanical means embodying co-acting cams, the latter serving to convert reciprocatory motion into rotary motion sufficient to turn a screw in the desired direction.

Needless to say, the art to which the invention relates is characterized by screw drivers having structural adaptations destined to accomplish the aforementioned results. Having such information in hand, I have evolved and produced what is believed to be a novel and improved choice and coordination of parts with a view toward providing a better and more satisfactory screw driver construction.

In carrying out the principles of the invention a structural arrangement is had which is simple and practical, easy and efficient to handle, and otherwise aptly devised to better accomplish the desired ends.

Other objects and advantages of the invention will become more readily apparent from the following description and the accompanying illustrative drawings.

In the drawings, wherein like numerals are employed to designate like parts throughout the views:

Figure 1 is a view, partly in section and partly in elevation, showing a screw driver constructed in accordance with the particular principles of the instant invention;

Figure 2 is a view, also in section and elevation, based on Figure 1 and of a fragmentary type showing the cams in a relation different from that illustrated in Figure 1;

Figure 3 is a cross section on the line 3—3 of Figure 2, looking in the direction of the arrows.

By way of introduction to the detailed description and briefly summarized, it will be seen that the invention, somewhat specifically considered, is characterized by an elongated hollow handle of cylindrical cross section, said handle having one end closed and adapted to be struck with a mallet or the like, a first sleeve closed on one end firmly secured into said handle with said closed end abutting the closed end of the handle, a second sleeve secured to said handle and having a reduced end portion rigidly attached to the other

end of said first sleeve, the other end portion of said second sleeve (at the end opposite said reduced portion) lying in a plane extending at an acute angle with respect to the longitudinal axis 5 of the handle to form a cam surface, a shank rotatable and slideable in said second sleeve, said shank having a screwdriver bit at one end and a head at the other end, said head being of greater diameter than the diameter of the bore 10 in said second sleeve, said headed end being situated in the bore in said first sleeve and having end in thrust contact with the closed end of said first sleeve when the shank is in its innermost position, a third sleeve firmly fixed on said shank 15 between said second sleeve and the open end of the handle, the end surface of said third sleeve opposed to the first-mentioned cam surface lying in a plane extending at substantially the same angle as the first-mentioned cam surface to 20 provide a second cam surface to coact with said first cam surface to impart rotation to said third sleeve and shank relative to said handle upon relative longitudinal movement of said shank and handle, the open end of said handle having an 25 insert secured therein, said insert having a bore to slidably receive said shank.

Referring now to the drawings by distinguishing reference numerals the shank of the screw driver is denoted by the numeral 5 and the bit by the numeral 6. The upper end of the shank is provided with an assembling impact receptive head 7. Spaced inwardly, or downwardly, from the head 7 is a sleeve 8. This is fixed on the shank and has its upper end provided with an inclined plane 9, functioning as a cam. For convenience, this part 8 may be identified as the shank rotating anvil. The handle means, generally denoted by the numeral 10, is slideable and rotatable in respect to the shank and sleeve and comprises a cylindrical jacket or casing 11 which completely houses the anvil 8. A closing plug 12 is secured in the lower end of said handle. A cap-shaped insert or sleeve 13 is press-fitted in the upper end of said handle and is provided 35 with a recess or cavity 14 to accommodate the head 7. The outer end portion of the handle is enlarged to form a head 15 which may be identified as an impact receiving element. This is adapted to be struck with a hammer, mallet or the like. A third metal or equivalent sleeve 16 is provided and has a reduced end portion 16a which fits into the recess and is welded or otherwise fixedly mounted in place in the bore or recess of said second-named sleeve 13. The lower surface of the sleeve 16 is also formed with an

inclined plane 17 which constitutes a cam. Obviously, the two face-to-face surfaces 9 and 17 constitute co-acting cams capable of imparting a quarter-turn to the shank—relative to the handle—when the end 15 of the handle is struck with the mallet.

It is understood that the handle means 10 as a unitary assemblage, includes the cylindrical grip 11, removable closing plug 12, cap-like insert or sleeve 13 and complementary sleeve 16. All of these parts are fixed together so that the handle means, as an individual device, provides not only a hand-grip and bearing for the shank 5, but also a driver for the driven element or sleeve 8.

Novelty is predicated on the sleeve means made up of the two sleeves 13 and 16 which are rigidly connected together with the sleeve 16 serving as a bearing or bushing for the turnable and slideable shank 5 and with the recessed portion of the sleeve 13 serving to house the headed end 7 of the shank 5. The closed end of the sleeve 13 serves to impart the desired impact action from 15 to 13 to 7. With the head 17 of a diameter greater than the diameter of the bore in the sleeve 16, it is evident that by removing the plug or insert 12 from the handle 11, the entire assemblage may be withdrawn from the handle. That is to say, the head 17 then comes to end-thrust contact with the feature 16a making it possible to pull all three sleeves with the shank 5 in a single operation.

It is understood that a screw driver constructed in accordance with the special handle means herein shown and described is useful in providing that extra twist or turn which is often so essential in handling screws, that is of the customary type wherein the head of the screw is provided with a kerf or bit-receiving nick. For instance, if a screw is rusty and so lodged in place that it may not be started and loosened by hand, using the ordinary screw driver, this improved screw driver will serve to start the screw for removal purposes. By the same token, if, in driving the screw home, an extra added turn or two is required to completely "sink" same, this improved screw driver will accomplish the desired results. In using it, a hammer or mallet is employed and the cams 9 and 17 are so arranged that by striking a blow against the impact head 15, the handle means 10 reciprocates along the shank 5, causing the cams 9 and 17, when they have been prearranged, to provide the rotary movement of the shank 5. Or, to put it otherwise, the drive and driven means 8 and 16 convert, through inclined companion planes 9 and 17, reciprocatory motion into rotary motion in an obvious manner.

A careful consideration of the foregoing description in conjunction with the invention as illustrated in the drawings will enable the reader

to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

I claim:

10 A screwdriver of the impact type shown and described comprising an elongated hollow handle of cylindrical cross-section, said handle having one end closed and adapted to be struck with a mallet or the like, a first sleeve closed on one end firmly secured into said handle with said closed end abutting the closed end of the handle, a second sleeve secured to said handle and having one end portion rigidly attached to the other end of said first sleeve, the other end portion of said 15 second sleeve, lying in a plane extending at an acute angle with respect to the longitudinal axis of the handle to form a cam surface, a shank rotatable and slideable in said second sleeve, said shank having a screwdriver bit at one end and a head at the other end, said head being of greater diameter than the diameter of the bore in said second sleeve, said headed end being situated in the bore in said first sleeve and having end-thrust contact with the closed end of said first sleeve 20 when the shank is in its innermost position, a third sleeve firmly fixed on said shank between said second sleeve and the open end of the handle, the end surface of said third sleeve opposed to the first-mentioned cam surface lying in a plane 25 extending at substantially the same angle as the first-mentioned cam surface to provide a second cam surface to coact with said first cam surface to impart rotation to said third sleeve and shank relative to said handle upon relative longitudinal 30 movement of said shank and handle, the open end of said handle having an insert secured therein, said insert having a bore to slidably receive said shank.
